CLOSED SYSTEM RECIRCULATING ASSEMBLY
 Gustave S. Levey, Houston, Tex., assignor to The Spec-Flo Manufacturing Corporation, Houston, Tex., a corporation of Texas

Filed Jan. 15, 1965, Ser. No. 425,808

7 Claims. (Cl. 239—127)

This invention relates generally to liquid distribution systems and more particularly to a novel and improved recirculating pressure system for airless paint spraying devices and the like.

The present invention is directed to a recirculating system for paint spraying and the like, arranged to maintain a relatively high pressure in the paint at the spray gun normally in the order of five hundred pounds per square inch to three thousand pounds per square inch.

In order to maintain the desired pressure at the spray gun a system according to the present invention includes an adjustable back-pressure relief valve which remains closed unless the pressure in the return line and in turn at the spray gun is equal to the adjusted pressure and then opens to modulate the recirculating flow, thus maintaining desired pressure. The system pump is provided with sufficient capacity to at least supply the maximum amount of paint required by the spray gun or guns at a pressure at least equal to the desired or adjusted pressure of the back-pressure relief valve. Normally the pump is selected to have excess capacity so that continuous recirculation is provided.

A heater is provided in the supply line from the pump to the spray gun which because of the recirculating flow maintains a uniform paint temperature even when the spray gun is intermittently operated. The relief valve is adjustable so that the user can select the correct operating pressure for the particular painting conditions and paint being used.

The adjustable back-pressure relief valve includes a valve element resiliently urged toward a seat by a spring, the compression of which is manually changed by turning an adjusting screw. A seal of the O-ring type seals against the adjusting screw preventing leakage. In order to maintain a positive pressure on the seal to insure proper sealing, a fixed back-pressure relief valve is provided in the circuit downstream from the adjustable back-pressure relief valve. This fixed relief valve is totally enclosed and requires no external dynamic seals so leakage does not occur therein. It performs the dual function of preventing air from entering the pressure system when the system is initially pressurized and also maintains a positive pressure on the seal around the adjusting screw insuring proper sealing thereof during operation.

It is an important object of this invention to provide a novel and improved pressurized liquid recirculating system including adjustable back-pressure relief valve means and fixed back-pressure relief valve means arranged to prevent air pollution of the system and leakage.

It is another important object of this invention to provide a recirculating pressure system for paint spraying and the like combining a pump, an adjustable back-pressure relief valve and separate pressure means for maintaining the discharge of the relief valve at a minimum pressure.

It is another important object of this invention to provide a novel and improved back-pressure system for recirculating pressure systems including an adjustable back-pressure relief valve operable to prevent recirculating flow at pressures below an adjusted pressure in combination with a fixed pressure back-pressure relief valve operable to maintain a minimum back-pressure in the adjustable valve.

It is another important object of this invention to provide a novel and improved recirculating system for airless spray guns and the like, including a pump operable to provide an excess of liquid paint at operating pressures, an adjustable back-pressure relief valve operable to maintain adjusted operating pressures during normal operation, and a fixed back-pressure relief valve operable to prevent discharge from the adjustable back-pressure relief valve at pressures below a minimum pressure.

It is still another object of this invention to provide a recirculating pressure system according to the last preceding object including heater means for controlling the temperature of the recirculating paint.

Further objects and advantages will appear from the following description and drawings wherein:

FIGURE 1 is a schematic illustration of the recirculating pressure system incorporating this invention; and

FIGURE 2 is an enlarged fragmentary view partially in section illustrating the structure of the back-pressure relief valve.

FIGURE 1 illustrates an embodiment of this invention utilizing a pump 10 operable to draw paint up an inlet line 15 from a paint container or drum 11. The pump illustrated is driven by a reciprocating air motor 12 and operates to supply paint under pressure to an outlet 13. The particular structure of the pump and its drive is disclosed in detail in my U.S. Patent No. 3,018,968. The particular pump structure is not critical to this invention except insofar as it cooperates with the remaining portions of the systems and it is merely necessary that the pump be operable to continuously provide a flow rate at least as great as that required for the operation of the spray gun at the required operating pressures of the spray gun.

The outlet 13 of the pump 10 is connected by a pressure line 14 to a heater 16 and from the heater 16 through a pressure line 17 to a spray gun 18. The spray gun 18 may be of any suitable type and reference may be made to my U.S. Patent No. 3,000,576, granted Sept. 19, 1961, for a detailed description of a preferred form of spray gun which may be used with a system incorporating this invention.

A return line 19 connects the spray gun 18 to a back-pressure relief assembly 21 which discharges to the intake 23 of the pump 10. Preferably, the intake 23 is of the type which prevents mixing of the recirculated paint with the paint in the container 11 so that only the paint being pumped out of the container is heated.

The pump 10 operates to deliver paint at operating pressure with a volume at least equal to the volume of paint sprayed by the spray gun 18 when the gun is operated. It should be understood that if desired more than one spray gun 18 may be connected to the pressure lines 17 and 19. In such installations the pump must have sufficient capacity for the combined operation of the spray guns. The back-pressure relief valve assembly 21 in combination with the pump functions as a pressure regulator maintaining a pressure at the spray gun equal to the operating pressure set by the adjustment of the back-pressure relief valve assembly.

Referring now to FIGURE 2, the back-pressure relief valve assembly 21 includes a main body 26 formed with an inlet chamber 27 and an outlet passage 28. The upper end of the body 26 is formed with a threaded opening 29 aligned with a bore 31 connecting the inlet chamber 27 and the outlet passage 28. An inlet port 32 is threaded to receive a fitting 33 connected through a T 34 to the return line 19. Therefore, the recirculating flow through the return line is connected to the inlet chamber 27. A pressure gauge 36 is mounted on the T 34 adjacent to the back-pressure relief valve assembly so that the user can determine the operating pressure. A bleed port 37,

also open to the inlet chamber 27, is threaded to receive a bleed valve 38 which in turn is provided with a bleed hose 39.

A regulating valve assembly 41 includes a valve body 42 threaded into the opening 29 and provided with a valve section 43 positioned within the bore 31. A seal 44 prevents leakage therebetween. A valve seat element 46 is mounted in the valve section 43 and pressed against a seal 48 by a threaded ring 47. A tubular stem support 49 is threaded into the valve body 42 and is internally threaded adjacent to its outer end to receive the adjusting stem 51. An O-ring 52, preferably formed of Teflon, provides a seal between the adjusting stem 51 and the inner wall of the stem support 49.

A ball valve 53 is carried by a valve stem 54 which extends into and is guided by the walls of an axial bore in the adjusting stem 51. A spring 56 extends between a thrust member 57 seated against the end face of the adjustable stem 51 and the valve stem 54 resiliently urging the valve stem and in turn the ball valve 53 toward the valve seat with a resilient force which is the function of the adjusted position of the adjusting stem. Therefore, the pressure in the inlet chamber 27 required to lift the ball valve 53 away from the seat 46 to allow flow through the device is a function of the adjusted position of the stem 51. If higher pressures are required the stem is rotated in a clockwise direction to screw it down into the body and if lower pressures are required anticlockwise rotation of the stem 51 causes it to reduce the spring force. Seals 55 and 55a are provided between the stem support 49, the valve body 42, and the body 26 of the assembly.

In order to insure that a minimum back-pressure is provided in the outlet passage 27 a fixed relief valve assembly 58 is threaded into an outlet opening 59. The assembly 58 includes a body 61 having a valve seat 62. A swivel nut 63 is mounted on the body 61 and threads onto a swivel fitting 64 mounted on the intake 23. A spring 66 extends between a shoulder on the swivel fitting 64 and a ball valve 67 resiliently urging the ball valve against the seat 62. Preferably, the elements of the fixed relief valve assembly are proportioned so that a pressure in the outlet passage 28 is in the order of twenty-five pounds per square inch before the ball valve 67 is lifted off of the seat 62 to allow flow. Therefore, the fixed relief valve assembly maintains a minimum pressure in the order of twenty-five pounds per square inch on the low pressure side of the adjustable relief valve 41 thereby maintaining a positive pressure on the seal 52 to insure its proper operation. Also, when the system is first pressurized air in the system is not permitted to flow into the system from the relief valve, even when vacuums occur.

In operation the pump 10 is started with the bleed valve 38 open to permit the air to escape from the system as the paint flows through the lines to the spray gun 18 and back to the relief valve. When all of the air is out of the lines and any required flushing is completed the bleed valve 38 is closed and continued pumping causes the pressure in the lines, the gun and the inlet chamber 27 to build up to a pressure determined by the setting of the adjustable stem 51. During the bleeding and normal operation of the system the pump produces a vacuum at the intake 23 since the paint level in the container is below the intake 23. During bleeding and initial pumping the valve assembly 58 remains closed and the vacuum at the intake 23 is not transmitted to the valve assembly 41.

As soon as operating pressure is reached the ball valve 53 is lifted away from the seat and the paint recirculates through the system with the pressure in the lines 14, 17 and 19, and in the spray gun 18 maintained at operating pressure. The pressure in the outlet passage 28 is maintained at a minimum of about twenty-five pounds per square inch due to the action of the ball valve 67.

If the fixed relief assembly 58 were not provided a vacuum would occur in the outlet passage 28. This vacuum or low discharge pressure, which would occur in the absence of the fixed pressure relief valve assembly 58, would cause working on the seal 52 and would result in leakage. However, back-pressure relief valve 58 prevents the intake vacuum of the pump from being transmitted to the adjustable relief valve assembly 41 and leakage at the seal 52 does not occur.

Although a preferred embodiment of this invention is illustrated, it is to be understood that various modifications and rearrangements of parts may be resorted to without departing from the scope of the invention as defined in the following claims.

What is claimed is:

1. A liquid pressure system comprising a source of liquid, a pump operable to pressurize liquid from said source and deliver it to an outlet, a liquid dispersing device, a supply pressure line connecting said outlet to said dispersing device, and return means connected to said dispersing device operating to return excess liquid for recirculation by said pump, said return means including first relief valve means adjustably operable to control operating pressure at said dispersing device, second relief valve means operable to restrict flow from said first relief valve means when the discharge pressure therefrom is below a predetermined minimum pressure, and a manually operable bleed valve in said return means upstream from said second relief valve means.

2. A recirculating pressurized system comprising a source of liquid at substantially atmospheric pressure, a pump having an intake connected to said source and being operable to deliver liquid under pressure to an output, a dispersing device, pressure lines connecting said output to said dispersing device and said dispersing device to said intake, adjustable back-pressure means in said pressure lines between said dispersing device and inlet operable to restrict flow therethrough when the pressure of liquid at said dispersing device is less than a predetermined adjusted pressure; said back-pressure means including an external control for adjusting the value of said predetermined pressure, and a seal preventing leakage therealong, secondary back-pressure means in said lines between said adjustable back-pressure means and intake operable to restrict flow therethrough when the pressure in said secondary back-pressure means is below a minimum pressure, said minimum pressure being above atmospheric pressure and below said predetermined pressure, said secondary back-pressure means being free of external dynamic seals.

3. A flow control assembly for use in recirculating paint spray systems comprising a body formed with an inlet adapted to be connected to a recirculation line, an outlet in said body, a relief valve in said body preventing flow between said inlet and outlet when closed and permitting flow therebetween when open, and adjusting stem threaded into said body from the exterior thereof and movable toward and away from said valve, a seal preventing leakage along said adjusting stem, a spring between said relief valve and said adjusting stem operable to urge said relief valve closed with a force determined by the position of said adjusting stem in said body, pressure in said inlet opening said relief valve when the pressure therein reaches a pressure determined by the position of said adjusting stem relative to said body and a pressure responsive flow control restricting flow from said outlet at pressures below a predetermined minimum pressure, said pressure responsive flow control being free of external dynamic seals.

4. A flow control assembly for use in recirculating paint spray systems comprising a body formed with an inlet adapted to be connected to a recirculation line, an outlet in said body, a first relief valve in said body preventing flow between said inlet and outlet when closed and permitting flow therebetween when open, an adjust-

ing stem threaded into said body from the exterior thereof and movable toward and away from said first relief valve, a seal preventing leakage along said adjusting stem, a spring between said first relief valve and said adjusting stem operable to urge said first relief valve closed with a force determined by the position of said adjusting stem in said body, pressure in said inlet opening said first relief valve when the pressure therein reaches a pressure determined by the position of said adjusting stem relative to said body, and a second relief valve mounted in said outlet, said second relief valve including a spring-biased valve element restricting flow from said outlet at pressures below a predetermined minimum pressure, said second relief valve being free of external dynamic seals.

5. A flow control assembly for use in recirculating paint spray systems comprising a body formed with an inlet adapted to be connected to a recirculation line, a bleed valve mounted on said body connected to said inlet, an outlet in said body, a relief valve in said body preventing flow between said inlet and outlet when closed and permitting flow therebetween when open, an adjusting stem threaded into said body and movable toward and away from said valve, a seal preventing leakage along said adjusting stem, a spring between said relief valve and said adjusting stem operable to urge said relief valve closed with a force determined by the position of said adjusting stem in said body, pressure in said inlet opening said relief valve when the pressure therein reaches a pressure determined by the position of said adjusting stem relative to said body, and a pressure responsive flow control mounted in said outlet restricting flow from said outlet at pressures below a predetermined minimum pressure.

6. A paint spray system comprising a source of paint, a pump operable to produce a vacuum at its intake to withdraw paint from said source and deliver paint under

5 pressure to an outlet, a spray gun, a supply pressure line connecting said outlet to said spray gun, and return means connected to said spray gun operating to return excess paint to the intake of said pump, said return means including first relief valve means adjustably operable to control operating pressure at said gun, second relief valve means operable to prevent flow from said first relief valve means when the discharge pressure therefrom is below a predetermined minimum pressure, and bleed valve means in said system ahead of said relief valve means, said bleed valve means being operable to an open condition to bleed air from said system and being closable to seal the pressure side thereof.

10 7. A flow control assembly as set forth in claim 6 wherein said first relief valve includes an adjusting member extending into said body from the exterior thereof and a seal preventing flow along said adjusting member, and said second relief valve is free of external dynamic seals.
